(57) CLAIM

The ornamental design for a table with privacy screen, as shown and described.

DESCRIPTION

FIG. 1 is a front partial perspective view of a table with privacy screen according to my new design;
 FIG. 2 is a front elevational view thereof;
 FIG. 3 is a side elevational thereof;
 FIG. 4 is a top plan view thereof; and,
 FIG. 5 is a bottom plan view thereof.
 Features shown in dashed lines form no part of the claimed designs.
